METHOD AND SYSTEM FOR TELEVISION
COMMUNICATION

Allen B. Du Mont, Upper Montclair, N. J., assignor to Allen B. Du Mont Laboratories, Inc., Passaic, N. J., a corporation of Delaware

Application January 11, 1938, Serial No. 184,407

17 Claims. (CL. 178—6.8)

My invention relates to improvements in methods and systems for television communication.

In the various television systems used heretofore and in which the scanning devices have been in the form of cathode-ray tubes, it has been necessary for two-way communication to employ at each station separate tubes for pick-up and viewing. That is, at each station in these systems, a cathode-ray tube having a photosensitive screen is used to develop the picture signals for transmission, and a cathode-ray tube having a fluorescent screen is used to produce an image of the view being transmitted from the distant station.

One of the objects of my invention is the provision of an improved system for two-way television communication, in which a single cathode-ray tube at each station serves both as a pick-up device to develop picture signals for transmission to the distant station and as a receiver or viewing device to produce an image of the view being transmitted from the distant station, thereby greatly simplifying and reducing the cost of the apparatus over that of the prior systems referred to in which separate pick-up and viewing tubes must be used at each station.

Another object of my invention is the provision of an improved television system in which the single scanning device at each station operates both as a pick-up device and as a viewing device and in such manner as to give simultaneous two-way communication between the two stations.

Other objects and advantages will hereinafter appear.

For the purpose of illustrating my invention, several embodiments thereof are shown in the drawings, in which

Figure 1 is a simplified, diagrammatic, plan view of a two-way television system constructed and operating in accordance with my invention;

Fig. 2 is a simplified, diagrammatic, side-elevational view, partly in perspective, of another two-way television system constructed and operating in accordance with my invention;

Fig. 3 is a simplified, diagrammatic, side-elevational view of still another two-way television system constructed and operating in accordance with my invention;

Fig. 4 is an enlarged, fragmentary, sectional view showing the screen construction in Fig. 3;

Fig. 4a is a view similar to Fig. 4, showing a modification; and

Fig. 5 is a simplified, diagrammatic view, partly in perspective, showing a modification of the system in Fig. 3 to give simultaneous two-way communication between two stations.

With reference to Fig. 1, the numerals 10 and 11 designate cathode-ray tubes disposed respectively at the stations A and B. Since these tubes

are similar in construction and manner of operation, only one will be described in detail.

The tube 10 comprises a photosensitive screen Pa and a fluorescent screen F_a disposed on opposite sides respectively of the tube axis, and means in the form of an electron gun for developing a ray 13 of electrons focused on and directed at either of the screens. The electron gun consists of a heater 14, a cathode 15, a modulating electrode or control grid 16, and anodes 17, 18 and 19.

For the purpose of causing the ray 13 to scan either of the screens Pa and F_a, a suitable sweep or deflecting circuit 20, which is common to the two tubes as shown and which operates at a suitable line frequency, is connected across the plates 21. Also, a suitable sweep or deflecting circuit 22, which is common to the two tubes as shown and which operates at a suitable frame frequency, is connected across the plates 23.

In transmitting from station A to station B, a light image of the view or object 24 for transmission is projected by a suitable lens system 25 onto the photosensitive surface of the screen Pa of the tube 10. Also, the electron ray 13 is made to scan only the screen Pa, whereas the electron ray 13b in tube 11 is made to scan only the fluorescent surface of the screen F_b in a manner hereinafter explained. Picture signals, accordingly developed in the well known manner by the tube 10, are supplied to an amplifier 26 through a lead 27 common to and coming from the screens Pa and F_a. The amplified picture signals are supplied through a line 28 and the closed switch 29 to the modulating electrode 16 of tube 11, whereby the intensity of the electron ray 13b is modulated to produce on the fluorescent screen F_b a visible image of the light image on the photosensitive screen Pa, since the two electron rays 13 and 13b are scanning the respective screens synchronously and in the same manner. The image so produced on the fluorescent screen F_b is seen from a point 30.

The picture signals developed by the tube 10 may be taken either from the screen Pa by the lead 27, or from a collector electrode 31 by a lead 32, depending upon the type of photosensitive screen used. That is, when a mosaic, photosensitive surface is used for the screen Pa, the collector electrode 31 is grounded and the picture signals taken from the screen Pa by the lead 27. When a secondary-emissive surface is used for the screen Pa, the latter is grounded and the picture signals are taken from the electrode 31 by the lead 32 and fed to the amplifier 26, the electrode 31 preferably being several hundred volts positive with respect to the screen Pa.

In transmitting from station B to station A, the switch 29 is opened and the corresponding switch 29_a at station A is closed. A light image of the view or object 24_b at the station B is projected by a suitable lens system 25_b onto the photosensitive

screen P_b . In this case, also, the electron ray 13_b is made to scan only the photosensitive screen P_b , and the electron ray 13 is made to scan only the fluorescent screen F_a . The operating action is the same as before. That is, the picture signals developed by the tube 11 are supplied to the amplifier 26_b through the lead 27_b , and the amplified picture signals are supplied through the line 28_b and the closed switch 29_a to the modulating electrode 16 of the tube 10 . Accordingly, on the fluorescent screen F_a at station A is produced a visible image, seen from the point 30_a , of the light image on the photosensitive screen P_b at station B.

The shifting of the electron rays 13 and 13_b to cause them to scan the photosensitive and fluorescent screens selectively, is accomplished by changing the positioning voltages applied to the deflecting plates for deflection of the rays at the line frequency. This may be done in a well known manner by changing a value of usual position-control resistance by means of a switch 33 , and making the respective polarities such that the electron rays shift in the proper directions. That is, with the switch 33 open, for example, the electron rays 13 and 13_b are caused to scan only the screens P_a and F_b , respectively, whereas with this switch closed, the electron rays 13 and 13_b are caused to scan only the screens F_a and P_b , respectively. It will be understood that instead of positioning the rays electrostatically, this may be done by means of a deflecting coil and a local source of D. C. potential.

The photosensitive and fluorescent surfaces have been shown as being formed on one piece of metal, with the common leads 27 and 27_b . In some cases, however, it may be advisable to have the photosensitive and fluorescent surfaces on separate plates with separate leads, or to mount the photosensitive surface and the fluorescent surface on separate sheets of mica or glass.

In the drawings, suitable values of voltage are designated for the control electrode 16 and the anodes 17 , 18 and 19 .

In the system shown in Fig. 2, the construction of the electron tubes 34 and 35 at the respective stations C and D is such as to provide for simultaneous, two-way communication between the stations. That is, each tube can transmit and receive at the same time.

In Fig. 2, the construction of the electron guns, and the sweep or deflecting circuits and connections for developing the electron rays 13_c and 13_d to cause these rays to scan the respective screen structures, are the same as in Fig. 1. However, in Fig. 2 the shape of the bulb of the tubes and the disposition of the photosensitive and fluorescent screens are different, as shown.

In Fig. 2, the photosensitive screens P_c and P_d are supported alongside the fluorescent screens F_c and F_d , respectively, with a slight separation and with separate leads from each screen. Also, the relative position of the two screens in one tube is the opposite of the relative position of the two screens in the other tube.

In the operation of this system, light images of the views or objects 24_c and 24_d at the two stations are projected simultaneously onto the respective screen structures.

Picture signals developed by the tube 34 are taken from the photosensitive screen P_c by the connection 27_c and supplied to the amplifier 26_c . The amplified picture signals are supplied through the transmission line 28_c to the modulating electrode 16_d of the tube 35 .

Picture signals developed by the tube 35 are

taken from the photosensitive screen P_d by the connection 27_d and supplied to the amplifier 26_d . The amplified picture signals are supplied through the transmission line 28_d to the modulating electrode 16_c of the tube 34 .

It will be assumed that the electron rays are deflected synchronously, and horizontally at a suitable line frequency, and vertically at a suitable frame frequency. On this account, and because of the opposite relation of the two kinds of screens at the two stations, it will be seen that each tube is caused to operate alternately to transmit picture signals to the other station and to reproduce a visible image in accordance with picture signals received from the other station, and that when one tube is functioning as a receiver the other tube is functioning as a transmitter.

For example, when the electron ray 13_d is directed at point 1 of the photosensitive screen P_d , the electron ray 13_c will be directed at point 1 of the fluorescent screen F_c . As the ray 13_d scans from point 1 to point 2 on the photosensitive screen P_d , a varying voltage is fed to the video amplifier 26_d from screen P_d to modulate the intensity of the ray 13_c accordingly as it scans the fluorescent screen F_c from point 1 to point 2 . However, when the ray 13_c is directed at the point 3 on the photosensitive screen P_c , tube 34 starts feeding picture signals to the video amplifier 26_c . As the ray 13_c scans the photosensitive screen P_c from point 3 to point 4 , the ray 13_d will scan the fluorescent screen F_d from point 3 to point 4 and its intensity will be modulated according to the picture signals developed during this time. This cycle of operation is repeated each time the electron rays scan the screen structures from left to right. The frame frequency is made sufficiently high so that no flicker appears in the picture or image produced on the fluorescent screens.

The same results as above can be obtained by first scanning screens F_c and P_d completely, and next scanning screens P_c and F_d completely. This can be done by deflecting the electron rays vertically at the line frequency and horizontally at the frame frequency.

In either method of scanning, the amplitude of one scanning voltage is twice that of the other, assuming a picture aspect ratio of 1:1.

The leads from the fluorescent screens F_c and F_d are provided so that if necessary it will be possible to bias these screens so that varying secondary emission from them will not couple into the photoelectric plate circuits and cause distortion.

In the system shown in Fig. 3, the same screen is utilized for pick-up and viewing, so that each tube can transmit and receive at the same time. In this system, therefore, there can be simultaneous, two-way communication between the stations E and F, as in Fig. 2.

In Fig. 3, the construction of the electron guns, and the sweep or deflecting circuits and connections for developing the electron rays 13_e and 13_f to cause these rays to scan the respective screen structures, are the same as in Figs. 1 and 2, the shape of the bulbs being more like that in Fig. 2.

The principal difference in the construction of the cathode-ray tubes 36 and 37 in Fig. 3, and those in Figs. 1 and 2, resides in the construction and characteristics of the screens P_eF_e and P_fF_f . That is, the entire effective area of each of these screens is both photosensitive and fluorescent, so that during each field or frame, the electron rays scan a surface which, at every ele-

mental area thereof, is both photosensitive and fluorescent.

One method of making the screens is illustrated in Fig. 4. The construction comprises a metal back or supporting plate 38 and a mica plate 39. A viscous insulating binder 40 is applied to the mica plate 39 through a screen of relatively fine mesh, so that at elemental, uniformly spaced areas over the mica surface there is some of the binder material. Crystals of the fluorescent material 41 are next dusted onto the binder material at the segregated elemental areas. Silver is now sputtered onto the fluorescent surfaces and the ordinary process for cesium cells carried out. This consists in properly oxidizing the silver, flashing the cesium pellet and then baking properly. There then results a mosaic surface which is both photosensitive and fluorescent.

Another method of making the screens in Fig. 3 is illustrated in Fig. 4a. In this case, the construction also comprises a metal back or supporting plate 38a and a mica plate 39a. Minute spots 5 of silver are by the well known half-tone process, printed on the mica surface, these spots being uniformly spaced over the surface and adjacent spots being very close to each other. Also printed on the mica surface by the same process, and with a fluorescent ink, for example, are minute, fluorescent spots 6. In the second printing operation, however, the placement is such that the minute fluorescent spots 6 are disposed in the spaces between the minute, silver spots 5. The silver spots 5 are now photosensitized in the same, usual manner as the minute, silver areas in Fig. 4. If desirable, the minute, fluorescent spots 6 may be printed on the mica surface first.

From the foregoing it will be seen that in the construction in Fig. 4, each effective elemental area or spot of the screen surface is both photosensitive and fluorescent, whereby during the scanning of each spot by the electron ray, the tube can function either as a transmitter or as a receiver. In Fig. 4a, however, the alternate effective elemental areas or spots of the screen surface are respectively only photosensitive and fluorescent, whereby the tube can function either as a transmitter or as a receiver.

In this system, there is a common video amplifier 42, and a double pole, double throw switch 43 is used to connect the amplifier for use with either of the tubes 36 and 37.

In transmitting from station F to station E, the switch 43 is placed in position x, and a light image of the view or object 24_f at station F is projected onto the screen PfF_f. Picture signals developed by the tube 37 are supplied to the input side of amplifier 42 by the lead 27_f and through switch 43. From the output of the video amplifier, the amplified signals pass through the switch 43 and connection 28_f to the control electrode 16_e of tube 36, and modulate the intensity of ray 13_e in accordance with variations in the picture signals. Since both electron rays are scanning the respective screens synchronously and in the same manner, there will be produced on the fluorescent screen of tube 36 a visible image of the object 24_f.

In transmitting from station E to station F, the switch 43 is placed in position y, and a light image of the view or object 24_e at station E is projected onto the screen PeFe. Picture signals developed by the tube 36 are supplied to the input side of amplifier 42 by the lead 27_e and

and through switch 43. From the output of the video amplifier, the amplified signals pass through the switch 43 and connection 28_e to the control electrode 16_e of tube 37, and modulate the intensity of ray 13_e in accordance with variations in the picture signals. There is then produced on the fluorescent screen PfF_e of tube 37 a visible image of the object 24_e.

From the foregoing, it will be seen that if the frame frequency is, for example, 60, and the switch 43 were actuated at a uniform rate to be in each of the positions x and y 30 times a second, and in these positions alternately and during a frame period, there will be simultaneous, two-way communication between the stations E 15 and F. That is, as in Fig. 2, each tube then functions alternately as a transmitter and as a receiver and at a rate at least as high as the rate for persistence of vision, and when one tube is functioning as a transmitter the other tube is 20 functioning as a receiver. A form of mechanical switch for this purpose, to replace the switch 43 in Fig. 3 is shown in Fig. 5. This comprises rotary contacts 44 and 45 fixed on a shaft 46 insulated at 47 and 48 and driven at the rate 25 of 30 revolutions per second by a synchronous motor 49. The contact 44 engages the fixed contacts 50 and 51 alternately and each at the rate of 30 times per second. The contact 45 engages the fixed contacts 52 and 53 alternately and each 30 at the rate of 30 times per second. In the position of the switch shown, tube 37 is functioning as a transmitter and tube 36 is functioning as a receiver. That is, picture signals from the screen PfF_f are supplied through the line 27_f, contacts 35 50 and 44 and brush 54 to the input side of the video amplifier 42. The amplified picture signals are supplied through the brush 55, contacts 45 and 52 and line 28_f to the control electrode 16_e of tube 36. The intensity of the ray 13_e is therefore 40 modulated in accordance with the picture signals from tube 37 to produce on the fluorescent screen PeFe a visible image of the object at station F. This action takes place during each half revolution of the shaft 46.

During the other half revolutions of the shaft 46 the reverse condition takes place, as will be seen from the drawings. That is, with the contacts 44 and 45 engaging the contacts 51 and 53, respectively, picture signals from the screen PeFe of tube 36 are supplied, through the line 50 27_e, contacts 51 and 44, brush 54, amplifier 42, brush 55, contacts 45 and 53, and line 28_e, to the control electrode 16_e of the tube 37, thereby producing on screen PfF_e an image of the object at 55 station E.

It will be understood that in lieu of the mechanical switch in Fig. 5, an electronic switch may be used for the same purpose.

It will be understood that the electron rays can 60 be deflected electromagnetically in one or both directions, instead of electrostatically, as shown and described.

In the various systems, furthermore, instead of using common sweep or deflecting circuits for the two stations, local sweep circuits may be provided at each station, and synchronizing pulses employed to hold these in step.

Also, the various signals can be transmitted 70 from one station to the other over radio circuits, rather than over a direct wire circuit.

Secondary-emission screens, with fixed patterns, may be used in lieu of the photosensitive screens in Figs. 1 and 2, and the collector elec- 75

trodes may be omitted and the picture signals taken from the fluorescent screens.

The system shown in Fig. 1 may be used as a regenerative amplifier by closing switches 29 and 29_a and adjusting the gain of the video amplifier at the viewing station so the system does not become overloaded. Assuming that station A is transmitting to station B, it is apparent that there will be a change in secondary emission of the fluorescent screen F_b, and this will cause a varying voltage to be fed into the video amplifier 26_b. Therefore, the electron ray 13 of tube 10 will be modulated, causing a greater signal output from the photosensitive screen P_a than would 15 otherwise be the case.

It will be understood that various modifications of the different embodiments of my invention described herein, are possible without departing from the spirit of my invention or the scope of 20 the claims.

I claim as my invention:

1. In a cathode-ray tube for television communication, screen structure characterized by the fact that at least part of the effective area 25 thereof is photosensitive at closely spaced elemental areas to form a mosaic of the photosensitive material and at least part of the effective area of said screen structure is fluorescent, means for developing a ray of electrons directed 30 at said structure, and means for deflecting said ray to cause the same to scan the photosensitive-fluorescent area directly.

2. In the art of television, the method of operation which consists in utilizing the photosensitive characteristic of screen structure to develop picture signals, utilizing the fluorescent characteristic of screen structure to reproduce a picture, and utilizing the same ray of electrons to scan directly the photosensitive and fluorescent 40 screen structure.

3. In a cathode-ray tube for television communication, screen structure characterized by the fact that at least part of the effective area thereof is secondary emissive and at least part 45 of the effective area thereof is fluorescent, means for developing a ray of electrons directed at said structure, means for deflecting said ray to cause the same to scan the secondary-emissive and fluorescent areas directly, and a collector electrode for supplying picture signals developed incidental to the scanning action.

4. In a system for television communication between two stations, a cathode-ray tube at one of said stations comprising a tube provided with 55 screen structure and with means for developing a ray of electrons focused on and directed at said structure, means for projecting onto at least part of the effective area of said structure a light image of the view for transmission to the other 60 station, and means for deflecting said ray to cause the same to scan said part of the screen structure to develop picture signals, at least part of the effective area of said screen structure being fluorescent, said tube being provided with means 65 for modulating the intensity of said ray in accordance with occurring variations in picture signals received at said station, said ray-deflecting means being operable to cause the ray to scan said fluorescent part of said screen structure to produce thereon a visible image.

5. In a cathode-ray tube for television communication, a photosensitive screen, a fluorescent screen, means for developing a ray of electrons focused on and directed at either of said screens, 75 means for projecting onto said photosensitive

screen a light image of the view for transmission, and means for controlling and deflecting said ray to cause the same to scan said screens selectively, said tube being provided with means for modulating the intensity of said ray in accordance with occurring variations in incoming picture signals.

6. In a cathode-ray tube for television communication, a tube, a photosensitive screen and a fluorescent screen disposed on opposite sides respectively of the tube axis, means for developing a ray of electrons focused on and directed at either of said screens, means for projecting onto said photosensitive screen a light image of the view for transmission, and means for controlling and deflecting said ray to cause the same to scan said screens selectively, said tube being provided with means for modulating the intensity of said ray in accordance with occurring variations in incoming picture signals.

7. In a system for television communication between two stations, cathode-ray tubes disposed respectively at said stations, each of said tubes being provided with screen structure and with means for developing a ray of electrons focused on and directed at said structure, means associated respectively with said tubes for projecting onto at least part of the effective area of the screen structure a light image of the view for transmission, means associated respectively with said tubes for deflecting the electron ray to cause the same to scan said part of the screen structure to develop picture signals, at least part of the effective area of the screen structure of each tube being fluorescent, each of said tubes being provided with means for modulating the intensity of the electron ray in accordance with occurring variations in picture signals supplied to the tube, the ray-deflecting means of each tube being operable to cause the electron ray to scan said fluorescent part of said screen structure to produce thereon a visible image, and means for transmitting signals from one of said stations to the other.

8. In a cathode-ray tube for two-way television communication, two screens supported alongside each other, one of said screens being fluorescent, means for projecting onto the other of said screens a light image of the view for transmission, means for developing a ray of electrons focused on and directed at said screens, means for modulating the intensity of said ray in accordance with occurring variations in incoming picture signals, and means for deflecting said ray to cause the same to scan each of said screens substantially the same number of times during each second.

9. In a cathode-ray tube for two-way television communication, a photosensitive screen and a fluorescent screen supported alongside each other, means for projecting onto said photosensitive screen a light image of the view for transmission, means for developing a ray of electrons focused on and directed at said screens, means for modulating the intensity of said ray in accordance with occurring variations in incoming picture signals, and means for deflecting said ray to cause the same to scan each of said screens substantially the same number of times during each second.

10. In a system for two-way television communication between two stations, cathode-ray tubes disposed respectively at said stations, each of said tubes being provided with a photosensitive screen and a fluorescent screen supported

alongside each other and with means for developing a ray of electrons focused on and directed at said screens, the relative position of the two screens in one tube being the opposite of the 5 relative position of the two screens in the other tube, means associated respectively with said tubes for projecting onto the photosensitive screens thereof light images of the views for transmission, each of said tubes being provided 10 with means for modulating the intensity of the electron ray in accordance with occurring variations in picture signals supplied to the tube, and means associated respectively with said tubes for deflecting the electron ray to cause the same 15 to scan the photosensitive screen and the fluorescent screen substantially the same number of times during each second.

11. In a cathode-ray tube for television communication, screen structure characterized by 20 the fact that the same effective area thereof is both photosensitive and fluorescent, means for developing a ray of electrons focused on and directed at said area, means for projecting onto said area a light image of the view for transmission, means for modulating the intensity of the electron ray in accordance with occurring variations in picture signals supplied to said tube, and means for deflecting the electron ray to cause the same to scan said area.

12. In a system for television communication between two stations, cathode-ray tubes disposed 25 respectively at said stations, each of said tubes being provided with screen structure characterized by the fact that the same effective area thereof is both photosensitive and fluorescent, each of said tubes being provided with means for developing a ray of electrons focused on and directed at the screen, means associated respectively with said tubes for projecting onto the 30 screen light images of the views for transmission, each of said tubes being provided with means for modulating the intensity of the electron ray in accordance with occurring variations in picture signals supplied to the tube, each of 35 said tubes being provided with means for deflecting the electron ray to cause the same to scan the screen, and means for transmitting to either tube the picture signals developed by the other.

13. In a system for television communication 40 between two stations, cathode-ray tubes disposed respectively at said stations, each of said tubes being provided with screen structure and with means for developing a ray of electrons focused on and directed at said structure, means associated respectively with said tubes for projecting onto at least part of the effective area of the 45 screen structure a light image of the view for transmission, at least part of the effective area of the screen structure of each tube being fluorescent, each of said tubes being provided with means for modulating the intensity of the electron ray in accordance with occurring variations in picture signals supplied to the tube, a sweep 50 circuit common to the cathode-ray tubes at both stations and operating to cause deflection of the electron rays of said tubes at a given and the same line frequency, and a second sweep circuit common to the cathode-ray tubes at both stations and operating to cause deflection of the 55 electron rays of said tubes at a given and the same frame frequency.

14. In a system for two-way television communication between two stations, a single scanning device at the first station and being in the

form of a cathode-ray tube, a single scanning device at the second station and being in the form of a cathode-ray tube, each of said tubes being provided with screen structure and with means for developing a ray of electrons focused on and directed at said structure, means associated respectively with said tubes for projecting onto at least part of the effective area of the screen structure a light image of the view for transmission, at least part of the effective area 10 of the screen structure of each tube being fluorescent, each of said tubes being provided with means for modulating the intensity of the electron ray in accordance with occurring variations in picture signals supplied to the tube, the cathode-ray tubes at each station being provided with means for deflecting the electron ray to cause the same to scan at least part of the effective area 15 of the screen structure to either function to develop picture signals for transmission 20 to the other station or function to produce a visible image in accordance with picture signals received from said other station, and means for causing each of said tubes to perform both of said functions at a rate at least as high as the 25 rate for persistence of vision.

15. In a system for two-way television communication between two stations, apparatus at the first station for either transmitting picture signals to the second station or producing a visible image in accordance with picture signals received from the second station, said apparatus comprising a single scanning device, and apparatus at the second station for either transmitting picture signals to the first station or producing 30 a visible image in accordance with picture signals received from the first station, said second-named apparatus comprising a single scanning device, each of said devices being in the form of a cathode-ray tube comprising screen structure 35 characterized by the fact that at least part of the effective area thereof is photosensitive and at least part of the effective area thereof is fluorescent, means for developing a ray of electrons directed at said structure, means for deflecting 40 said ray to cause the same to scan said photosensitive-fluorescent screen structure, and means for modulating the intensity of said ray in accordance with occurring variations in incoming 45 picture signals.

16. In a cathode-ray tube for two-way television communication, screen structure, means for developing a ray of electrons directed at said structure, and means for deflecting said ray to cause the same to scan the adjacent screen surface, each effective elemental area of said surface being provided with a photosensitive and fluorescent spot of the same elemental dimension whereby during the scanning of each elemental area by 50 said ray the tube can function either as a transmitter or as a receiver.

17. In a cathode-ray tube for two-way television communication, screen structure, means for developing a ray of electrons directed at said structure, and means for deflecting said ray to 55 cause the same to scan the adjacent screen surface, the alternate effective elemental areas of said surface being respectively only photosensitive and only fluorescent whereby during the scanning action said tube can function either 60 as a transmitter or as a receiver.
